SLOW BREAK SWITCH

Robert F. Sampson, Bridgeport, Conn., assignor
to General Electric Company, a corporation of
New York

Application November 9, 1937, Serial No. 173,619

4 Claims. (Cl. 200—151)

This invention relates to switches of the slow-break type for use with alternating current.

It is an object of the invention to provide an improved construction and arrangement of switches of this type wherein means are provided to separate the switch contacts a small distance until the current wave passes through a zero point thereby interrupting the current and extinguishing the arc across the contacts occasioned by the current interruption.

Referring to the drawing, Fig. 1 is an elevation of the assembled switch; Fig. 2 is a vertical section through the switch; Fig. 3 is a sectional view through the switch in closed position partly along the line 3—3 of Fig. 1; Fig. 4 is another sectional view through the switch in open position partly along the line 4—4 of Fig. 2; and Fig. 5 is a perspective view of the switch actuating mechanism.

The switch, as shown in Figs. 1 to 4, inclusive, 20 has a housing 10 formed of molded composition, or the like, which is provided with a bottom 11 having upstanding abutments 12 and 13 at each end adjacent the end walls 14 and 15, respectively. The abutment 12 and the wall 14 form a recess 16 which receives the terminal end of a switch blade 17. The blade 17 is formed of a strip of spring bronze and is bent at an angle, as best shown in Figs. 3 and 4, and placed within the housing with the terminal end seated in the 25 recess 16 with the sides in close engagement with the abutment 12 and end wall 14. In this manner the blade is held securely within the housing without the use of separate fastening means such as rivets, or the like. Similarly, the abutment 13 and end wall 15 form a recess 18 adapted to receive the terminal end of a bronze switch blade 19 which is bent at an angle and disposed in the 30 housing 10 along side the blade 17. The abutment 13 and wall 15 closely engage the blade 19 when it is inserted into the recess 18 and hold the blade securely within the housing. The blades 17 and 19 are provided with terminal screws 17' and 19' for connection to a line circuit, the heads of the screws being disposed in recess 14' and 15' 35 formed in the end walls 14 and 15.

In order to prevent the blades 17 and 19 from becoming unseated from the recesses 16 and 18 and in order to enclose the switch mechanism, the housing is provided with a cover 20 which 40 engages the upper edges of the blades and retains them in the recesses. The cover may be formed from sheet fiber and is clamped to the top of the housing by means of a bracket 21 having clamping prongs 22 engaging in grooves 23 formed in the side walls 24 and 25 of the housing. Each

side wall is formed with ribs 26 extending into the interior of the housing, the ribs giving the side walls a thickness sufficient to provide for the grooves 23 which are formed within the ribs 26. The grooves extend from the bottom of the casting to a point short of the top where they terminate to form engaging surfaces for the bent-over portions 27 of the prongs 22. To provide a supporting means for the switch a threaded sleeve 28 is mounted upon the bracket 21 and is secured 10 thereto by a bent-over flange 29. The sleeve may be inserted into an opening in a mounting panel, or the like, and secured to the panel by a nut (not shown) threaded upon the sleeve.

The mechanism for operating the switch blades 15 includes a handle 30 pivoted within the sleeve 28 by a pin 31 and adapted to oscillate within the walls of the sleeve from "off" to "on" position. Depending from the handle 30 is a switch blade 20 actuating arm 32 and a slider 33 both of these 25 elements being mounted on the pin 31 and being fastened to the handle by means of the crimped-over projections 34, shown in Fig. 5. The slider and actuating arm are in intimate contact and oscillate as a unit with the handle 30. The actuating arm 32 is formed of insulating fiber and carries at its outer end a projection 35 having a shank 36 passing through the arm and being secured thereto by means of an upset head 37. The head is housed within an opening 38 formed in 30 the slider 33; this construction permits the slider and arm to lie flat against each other and forms a protecting wall for the projection head. The slider 33 is punched from insulating fiber, paper, or the like. To insure proper engagement between the slider and the switch blades the arm 32 is formed with a cutout recess 32'.

Figs. 3 and 4 illustrate the manner in which the slider and projection cooperate with the switch blades. The switch blades 17 and 19 are 40 provided with opposed contacts 38' and 39 which may be made of copper coated with silver and which are normally in engagement under the spring action of the switch blades, as shown by Fig. 3. In addition, the switch blade 19 is provided with a depression 40 to receive the projection 35, together with a cam or inclined surface 41 which likewise coacts with the projection. To support the projection against the blade the housing 10 is formed with a bearing surface 42 upon 50 which the slider 33 and arm 32 rest so that the projection 35 is disposed between the blade 19 and the surface 42.

With the contacts 38 and 39 in engagement the switch is closed and the handle 30, together

with the slider 33 and actuating arm 32, take the position shown by Figs. 1 and 3 with the projection 35 in engagement with the inclined surface 41 of the blade 19. As the switch is moved 5 to "open" or "off" position the projection 35 moves along the inclined surface 41 and by bearing against the surface 42 springs the blade 19 thereby opening the contacts 38 and 39. The contacts need be opened a small distance, only, 10 to cause opening of the circuit, because as the current wave passes through a zero point the current flow across the contacts will be interrupted. In like manner, any arc which may be formed between the contact points will be extinguished immediately as the current wave passes through a zero point. By opening the contacts a small distance, only, a minimum of 15 energy is released in the arc during separation of the contacts. As the projection moves along the 20 spring blade the insulating slider 33 will be inserted between the contacts 38 and 39 as they are sprung apart, the slider thus acting as an additional safeguard in extinguishing the arc. In this position the actuating arm 32 will straddle 25 the contact 39 the latter nesting in the recess 32' cut from the actuating arm.

Theoretically, it is not necessary to interpose the insulating slider between the contacts in order to extinguish the arc; this is done as an added precaution in case the spring contact 19 loses its temper, and separation of the contacts by projection 35 is not to be relied on. However, the slider will act to extinguish the arc in cases where the switch is operated extremely fast so that the time of switch travel is less than the time interval of a half cycle of the current. In addition, the slider acts to clean the contacts as it is moved to and fro over their surfaces.

Further movement of the switch handle permits the projection 35 to center itself in the depression 40 thereby holding the switch in "off" position and allowing the contact 39 to close toward the other resiliently clamping the insulating slider 33 between the contacts. This position is shown by Figs. 2 and 4.

In spite of the fact that the switch is operated by hand it is not possible to leave it partially opened. The switch is either "on" or "off". If the projection 35 is left half way along the inclined surface 41 the spring action of the blade

19 will cause the projection to move along the surface to the left in Fig. 3, to permit the contacts to close. However, if the projection is left in mid-position on blade 19, it will remain there and the switch will remain in the "off" position. 5

What I claim as new and desire to secure by Letters Patent of the United States is:

1. In a switch, a housing having a bearing surface therein a fixed contact member and a movable contact member, said movable contact member having a cam portion, cam-operating means movable along said bearing surface and coacting with said cam portion to separate said contacts, an insulating slider movable co-extensively with said means and adapted to be inserted between 10 said contact blades when in separated position, and means to move said cam-operating means and slider. 15

2. In a slow-break switch, a fixed contact member and a movable contact member, said 20 movable contact member having an inclined portion and a depressed portion, operating means including a projection movable along said inclined portion to separate said contacts, and an insulating slider movable co-extensively with 25 said projection, said operating means being adapted to insert said slider between said contacts and simultaneously position said projection in said depressed portion.

3. In a switch, a fixed blade and a movable 30 blade, opposed cooperating contacts mounted on said blades, said movable blade having a cam surface and a depressed portion, a pivoted arm, a projection mounted on said arm and cooperating with said cam surface to open said contacts, 35 a pivoted insulated member movable with said arm and insertable between said contacts as said abutment moves along said cam surface and into said depression, said arm having a cutout portion to receive said movable contact, and means for 40 moving said arm and member.

4. In a slow break switch, a housing having a bearing surface therein, contact blades mounted in said housing, one of said blades having a cam surface, a projection movable along said bearing 45 surface and engaging said cam surface to open said contact blades, and means to operate said projection.
